UNITED STATES PATENT OFFICE.

FELIX JOTTRAND, OF UCCLE, BELGIUM.

OXYHYDROGEN-BLOWPIPE.

No. 808,382.

Specification of Letters Patent.

Patented Dec. 26, 1905.

Application filed October 6, 1902. Serial No. 126,007.

To all whom it may concern:

Be it known that I, FELIX JOTTRAND, engineer, a subject of the King of Belgium, residing at Uccle, near Brussels, in the Kingdom of Belgium, have invented certain new and useful Improvements in Oxyhydrogen-Blowpipes, of which the following is a specification.

This invention relates to an improved construction of oxyhydrogen - blowpipes, the main object of which is to provide apparatus capable of being used safely for gases subjected to unequal pressures, so that the same apparatus may, for example, be employed for oxygen at high pressure and for illuminating-gas at a relatively low pressure, a further object of the invention being to insure a perfect mixture of the gases employed whether at equal or unequal pressures.

With these objects in view the invention consists, in the combination with any mixing-chamber, of an injector acting by suction, the characteristic feature of which is that the supply of gas at high pressure takes place through a twyer or nozzle, the gas entering a suction-chamber communicating both with the part supplying gas at comparatively low pressure and with the mixing-chamber proper; and the invention further comprises a special form of mixing-chamber, the distinguishing feature of which is its gradually - narrowing cone-shaped internal surface, the object of which is to retard the issue of gas through the orifice or burner of the blowpipe as much as is necessary to insure an intimate mixture of the gases.

Referring to the annexed drawings, Figure 1 is a longitudinal section of a blowpipe constructed according to my invention. Fig. 2 is a front view of a detail of the blowpipe, showing the inlet-orifices for the gases in the suction-chamber.

The improved blowpipe comprises a mixing-chamber 1, attached to a support or socket 2, provided with a central passage 3 of pre-calculated size, opening at one end into the mixing-chamber 1 and at the other end into a chamber 4 of predetermined dimensions, which is herein described as the "suction-chamber" and is closed by a partition or diaphragm 5, provided with an extension 6, which is so perforated in its central part as to constitute a passage 7 for the gas subjected to the higher pressure. The said passage 7 terminates within the suction-chamber 4 in a twyer 11, (nozzle or nipple,) whereof the ori-

ifice is situated at very little distance from the passage 3, through which the suction-chamber communicates with the mixing-chamber, while its other end joins the tube 8, which supplies high-pressure gas. The tubular portion 6 is surrounded by a chamber 9, connected to the passage 10, which supplies gas at lower pressure. This chamber 9 communicates with the suction-chamber 4 through a port 10, provided in the diaphragm 5, which closes the said suction-chamber 4 in the rear. It will readily be seen that, owing to this construction, whatever may be the shape of the mixing-chamber the blowpipe above described will be capable of operating without any danger with gases subjected to unequal pressure—say oxygen compressed at a high degree of pressure and illuminating gas used at the ordinary pressure at which it is supplied through the city mains. 75 For inasmuch as the gas under pressure delivered into the suction-chamber 4 through the passage 7 and issuing from such chamber through the nipple 11 will cause suction to take place within such chamber upon its entering the passage 3, leading to the mixing-chamber, the gas subjected to the lower of the two pressures will be drawn by suction from the chamber 9, through the port 10, and into the mixing-chamber, into which it will be carried away by the gas undergoing the higher pressure without any fear of the low-pressure gas being forced back by the high pressure. In order to insure a perfect mixture of the gases thus conducted into the mixing-chamber 1, I construct this chamber with a conical section, the diameter of the tube decreasing gradually and to a uniform rate toward the outlet-orifice 12 of the burner of the blowpipe. 90

Having thus described my invention, what I claim is—

1. In oxyhydrogen-blowpipes in combination: a mixing-chamber, a suction-chamber, the said suction-chamber communicating with the mixing-chamber by aid of a passage of precalculated size and being provided with a port for supplying gas at a relatively low pressure, a nozzle placed at the center of the suction-chamber and a tube supplying a relatively high-pressure gas to the said nozzle, substantially as described and for the purpose set forth.

2. In oxyhydrogen-blowpipes in combination: a mixing-chamber, a socket provided with a central passage, a suction-chamber communicating with the mixing-chamber by aid of

said central passage, a partition closing the suction-chamber at the rear, the said partition being provided with a perforated extension in its central part, and the said perforated extension forming a nozzle in the suction-chamber and being connected to a tube supplying a relatively high-pressure gas, and a chamber surrounding the perforated extension the said chamber communicating with the suction-chamber and being connected to a tube supplying a relatively low-pressure gas, substantially as described and for the purpose set forth.

3. In oxyhydrogen-blowpipes in combination, two gas-inlets, a chamber of small capacity in which open the said gas-inlets, a mixing-chamber communicating with the chamber of small capacity and having at its part adjacent to the chamber of small capacity its largest cross-section, the section of the mixing-chamber narrowing gradually from the part adjacent to the chamber of small capacity to the end remote from said chamber.

4. In oxyhydrogen-blowpipes, in combina-

tion, a mixing-chamber having a cone-shaped internal surface, a socket for said mixing-chamber, the said socket being provided with a central passage, a suction-chamber communicating with the mixing-chamber by aid of said central passage, a partition closing the suction-chamber at the rear, the said partition being provided with a perforated extension in its central part and the said perforated extension forming a nozzle in the suction-chamber and being connected to a tube supplying a relatively high-pressure gas, and a chamber surrounding the perforated extension, the said chamber communicating with the suction-chamber and being connected to a tube supplying a relatively low-pressure gas, substantially as described and for the purpose set forth.

In witness whereof I have hereunto set my hand in presence of two witnesses.

FELIX JOTTRAND.
